SILO DOOR

Martin Goldbeck, Kansas City, Mo.

Application August 4, 1941, Serial No. 405,401

5 Claims. (Cl. 20—1.4)

My invention, which relates generally to the construction of silos, has particular reference to the doors thereof.

Primarily my present invention has for its objects: to provide a strong, rigid door-frame having provision for cooperating with the staves of tiles comprising the subject matter of my application for patent filed June 20, 1941, Ser. No. 399,025, and that of my Patent No. 2,247,836, issued July 1, 1941; to provide a door-frame by means of which the tensile stresses of the hoops, intercepted by the door openings are absorbed in the door-frames proper; and to provide a door-frame having provisions for supporting a ladder unit overlying the masonry interval between the doors in silos where such interval occurs.

Other objects will in part be obvious and in part be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawings, in which:

Fig. 1 is a front elevation of a door unit embodying my invention, the silo hoops being indicated in dotted lines.

Fig. 2 is a horizontal section on the line 2—2 of Fig. 11, the adjacent staves of the silo being shown in horizontal section.

Fig. 3 is a detail section on the line 3—3 of Fig. 1, showing one of the door latches.

Fig. 4 is a detail section on the line 4—4 of Fig. 1.

Fig. 5 is a detail vertical section of two frames of a continuous door arrangement.

Fig. 6 is a detail side elevation of the frame per se shown in Fig. 1, looking from left to right in that figure.

Fig. 7 is an enlarged detail front elevation showing the interlocking of the upper and lower frames.

Fig. 8 is a vertical section on the line 8—8 of Fig. 7.

Fig. 9 is a detail front elevation of a portion of a modified frame.

Fig. 10 is a detail section on line 10—10 of Fig. 9.

Fig. 11 is a detail elevation of a portion of a silo showing the construction where the doors are not continuous.

Fig. 12 is a detail perspective view of one of 55 as at 15^a in Fig. 9.

the ladders which are supported by the door frames over intervening masonry.

Fig. 13 is a detail cross section on the line 13—13 of Fig. 1.

5 In the drawings, in which like numerals of reference indicate like parts in all the figures, 1 represents the inner faces of the tiles constituting the staves adjacent the sides of the door-frames, 2 the outer faces, and 3 the vertical side walls having grooves 4 to receive expansion-joint strips 6, grooves 5 to receive the locking medium 7, and grooves 8 to receive the strips of wood or other dam strips 9, all of which may be of similar construction to that—for example—10 of the tiles-staves of my application Ser. No. 399,025.

The door-frame (for an individual opening) comprises a rectangular casting composed of top, bottom and side walls 10. The top and bottom 15 walls are flat and have plane outer faces 20, save for the presence at the sides and center of hoop-seating lugs 17, having arcuate seats 18 for the silo-encircling hoops 23.

The sides of the frame 10 have vertical ribs 25 11, front flanges 15 and vertical grooves 12, the grooves 12 serving to cooperate with the grooves 8 to receive the wood (or other suitable material) dam strips 9.

The vertical sides of the frame 10 also have 30 surfaces 13 to oppose the grooves 5 of the adjacent staves and convex surfaces 14 to oppose the grooves 4 and cooperate therewith and with the expansion strips 6. The spaces between the surfaces 13 and the adjacent staves are filled 35 with the slab-locking medium 7.

On the inner walls (top, bottom and sides) of the frame 10 are the door stops formed by the ribs 16.

The frames, which are of such heights that the 40 door openings interrupt hoops 23, are provided with integral lugs 22 through which the ends of the silo-encircling hoops are passed and placed under tension by means of nuts 24, thus tending to squeeze the walls 1 at the sides of the door openings in the direction of the arrows *a* in Fig. 2. Those frames which have the lugs 22

45 also have front flanges 15 of varying widths, the width depending on the number of lugs 22. For instance, when three lugs to a side are necessary, the flanges 15 are of the maximum width shown, but when only one or two lugs per side are used the flanges need to be only about one-half of those shown in Fig. 1, and when no lugs are necessary the flanges are narrowed still further, 50 as at 15^a in Fig. 9.

When a continuous series of door units is employed, i. e., where one unit is placed directly on top of another, without staves or tiles intervening (see Figs. 5, 7 and 8), one unit may have the lugs 17 (top and bottom) while the next adjacent units may have lug sockets 19 into which the lugs 17 set, horizontal expansion joints 21 being inserted between the superposed units, as shown. Instead of one unit having the lugs 17 and the adjacent units having the lug sockets 19, one unit, obviously, may have lugs 17^a, say on the bottom wall, and sockets 19^a on the top wall (see Fig. 9) if desired.

When a continuous series of doors is employed in the silo, single rung ladders 38 (Fig. 5) may be employed and their vertical legs 39 then pass through the lower lugs 31 of one frame unit and the upper lugs 31^a of the unit below, and thus cooperate with the lugs 17 and sockets 19 (or 17^a and 19^a) in locking adjacent frames together.

Sockets 25 are provided in the top and bottom walls of the frame 10 to receive the pivot ends 27 of the door-carrying U-shaped member 26, bearings 28 being provided for the member 26 on the door 29. The axes of the sockets 25 align with each other and the axes of the bearings 28 align with each other, the axes of sockets 25 and bearings 28 being vertically disposed.

The door 29 is formed of front and back sections composed of horizontal and vertical tongue and grooved boards respectively, with an acid-resisting gasket sheet 30 located between them.

Suitable latches 36 are provided and pivoted at 37 to the door to engage over the side door stops 16.

The frame 10 is preferably provided with top and bottom ladder supporting lugs 31 to receive the down-turned ends 34 of the rearwardly projecting portions 33 of the ladder-sides 32 to which the rungs 35 are welded, as at *w*.

The ladders 33, 33, 34, 35 overlie the masonry intervals between adjacent door frames, while the doors 29 have individual ladder elements of any approved construction, such, for example, as that illustrated in Figs. 1, 11 and 13, by reference to which it will be seen that brackets 48 have feet 41 bolted at 42 to each door, and a rung 43 welded to the brackets.

In Figs. 9 and 10 those parts which correspond to similar parts in the other figures bear the same reference numbers followed by the index letter *a*.

From the foregoing it will be seen that when the hoops 23 are tightened the flanges 15 will be held up tight against the faces of the adjacent staves and, owing to the rigidity of the frame 10, the tension of the hoops 23 which are attached to the lugs 22 is absorbed by the frame, which, in effect, serves as a non-stretchable link between the ends of those hoops. Also, the construction of the sides of the frame provides a bonding and sealing of the joints between the frame and staves which is as effective as that between adjacent staves.

Other advantages of my improved door unit construction will be apparent to those skilled in

the art, and changes in the proportions of parts and other modifications than those heretofore mentioned can be made without departing from the spirit of my invention and from the scope of the appended claims.

What I claim is:

1. In a silo, a plurality of superposed door frames each including top, bottom and side walls, expansion joint slabs located between the frames, interlocking hoop-receiving lugs and sockets connecting adjacent frames together, a top and a bottom forwardly projecting apertured lug in vertical alignment with each other at each side of the frame, and means passing through said apertured lugs for securing the frames together.

2. In a silo, a plurality of superposed door frames each including top, bottom and side walls, expansion joint slabs located between the frames, interlocking hoop-receiving lugs and sockets connecting adjacent frames together, a top and a bottom forwardly projecting apertured lug in vertical alignment with each other at each side of the frames, and means passing through said apertured lugs for securing the frames together, said means overlying the hoop-receiving lugs.

3. An article of manufacture comprising a cast metal door frame of a rectangular form having continuous-hoop receiving lugs projecting from one vertical end of the frame and corresponding lug-receiving recesses in the other vertical end of the frame, by virtue of which when one frame is set on top of another frame of like construction the frames will be interlocked against transverse displacement of one frame with respect to the other frame.

4. An article of manufacture comprising a cast metal door frame of rectangular form having continuous-loop receiving lugs projecting from one vertical end of the frame and corresponding lug-receiving sockets in the other vertical end of the frame, and apertured lugs projecting forwardly from the face of the frame and located adjacent the top and bottom portions of the frame, said apertured lugs, when two or more frames are assembled, serving to receive elements to connect the lugs of one frame to the lugs of the adjacent frame or frames thereby to prevent forward and backward movement of one frame on another.

5. An article of manufacture comprising a cast metal door frame of a rectangular form having continuous-hoop receiving lugs projecting from one vertical end of the frame and corresponding lug-receiving recesses in the other vertical end of the frame, by virtue of which when one frame is set on top of another frame of like construction the frames will be interlocked against transverse movement of one frame on the other, the hoop-receiving lugs of the frame being of greater depth than the lug-receiving recesses, by virtue of which when one frame is set on top of another frame of like construction with the lugs of the one in the recesses of the other the frames will be spaced apart sufficiently to receive between them a sealing material.

MARTIN GOLDBECK.
